UNITED STATES PATENT OFFICE.

CHARLES D. BENNETT, OF KIRKWOOD, MISSOURI.

ROTARY ENGINE.

SPECIFICATION forming part of Letters Patent No. 687,514, dated November 26, 1901.

Application filed June 3, 1901. Serial No. 62,879. (No model.)

To all whom it may concern:

Be it known that I, CHARLES D. BENNETT, of the city of Kirkwood, St. Louis county, State of Missouri, have invented certain new and useful Improvements in Rotary Engines, of which the following is a full, clear, and exact description, reference being had to the accompanying drawings, forming a part hereof.

This invention relates to rotary engines; and it consists of the novel construction, combination, and arrangement of parts hereinafter shown, described, and claimed.

The object of this invention is to provide an improved rotary engine consisting of a piston mounted between stationary cylinder-heads, with corresponding chambers formed in the sides of the piston and in the cylinder-heads, into which the steam enters to rotate the piston.

Another object is to provide a number of abutments or valves located within depressions formed in the piston and in the cylinder-heads, against which the steam is driven to rotate the piston, and to provide means whereby the said abutments or valves will be forced into the depressions in which they are carried to permit them to pass each other while the piston is rotating.

Figure 1 is a side elevation showing my improved engine complete. Fig. 2 is an end view. Fig. 3 is a sectional view showing the arrangement of the different parts comprising the engine. Fig. 4 is a cross-section. Fig. 5 is a plan view. Fig. 6 is a perspective view showing one of the cylinder-heads. Fig. 7 is an enlarged detail view showing the location of the entrance-ports.

In the construction of my improved engine I provide the cylinder-heads 1, spaced a suitable distance apart and connected together by means of the cylinder or casing 2, the latter inclosing the rotary piston, which is located between the cylinder-heads 1. The inner faces of the cylinder-heads are cut out, as indicated by 3, forming chambers which become gradually deeper from the center toward the outer edges. Within each of said depressions or chambers is formed a segmental cam-surface 4, the inner surface of which is in alinement with the edge of the ring around the chamber 3. A depression 5 is formed within the cam-surface 4, and a spring-actuated

valve or abutment 6 is located within the said depression 5 and is pivoted at its inner end by means of the pin 7. A spring 8, located within the depression 5, actuates the said valve or abutment inwardly, as clearly shown in Fig. 4.

9 indicates the piston, which is located between the cylinder-heads 1 and is keyed upon the shaft 10. In each side of the cylinder 9 is formed a chamber 11, which chambers are identical with the chambers 3, above described, except that the cam-surfaces within the chambers 11 are diametrically opposite. 60 A recess 12 is formed in each of the cam-surfaces in the piston, and a valve or abutment 13, corresponding to the valves 6, above described, is carried in each of the recesses 12, and the said valves or abutments are actuated outwardly into the chambers 3 by means of the springs 14. These valves are pivoted at their inner ends, as clearly shown in Fig. 4. It will be noticed from this that when the valve or abutment 13 on one side of the piston is adjacent to the valve 6 the valve 13 on the opposite side of the piston is diametrically opposite from the corresponding valve in the cylinder-head. Hence it follows that the steam is driven against one or 70 the other of the valves all the time, and the piston will thus be kept in continuous motion. It will be noticed by referring to Fig. 4 that at the center the cylinder-heads bear close against the sides of the piston, but at 85 the outer edge of the piston a space is left, so that the sides of the piston do not bear directly against the sides of the cylinder-heads. By such an arrangement the friction to be overcome by the rotation of the piston is reduced to a minimum and the packing 15, which is carried by the piston, will prevent the escape of any of the steam through this space. This packing may be spring-actuated, as shown in Fig. 7, if desired.

As above stated, there are cam-surfaces formed in the chambers 3 corresponding to the cam-surfaces 4, and hence when the piston is rotated the said cam-surfaces within the chambers 3 will pass the cam-surfaces 4 and will force the valves or abutments 6 back into the recesses 5 in opposition to the springs 8, while the valves 13 will be forced into the recesses 12 by the cam-surfaces 4, and thereby

permit the two valves 6 and 13 to pass each other. In Fig. 4 two of the valves are shown in the act of passing each other, the springs 8 and 14 being compressed. After the cam-surfaces have passed the valves are again actuated by their springs and forced into the chambers to act as abutments for the steam. These valves fit snugly within the recesses within which they are carried and cannot be come dislocated.

On the upper side of the cylinder is mounted a steam-chest 16, within which the valves controlling the admission and exhaust of the steam are located. At each side of the steam-chest is formed a valve-chamber 17, within which the valves controlling the admission and exhaust of the steam to that side of the piston are located. Two ports 18 lead from each of the valve-chambers 17 through the cylinder-head 1 into the chambers 3 and 11. Two ports are provided, so that the piston may be driven in either direction, and they lead to different sides of the abutments 6, which, as shown in Fig. 4, are at the upper side of the cylinder. When the steam is admitted through one of the ports 18, the other is used as an exhaust, as will hereinafter appear. A valve 19 is located in each of the valve-chambers 17 and is provided with two openings 20, which may be brought in communication with the ports 18. A recess 21 is formed in the under side of the valve 19, and when one of the openings 20 registers with the port 18 the recess 21 communicates with the other port 18, and thereby forms an exhaust-passage to permit the steam to pass from within the cylinder through the port 18 and the recess 21 and through an opening 22, formed in the inner wall of the valve-chamber. The steam may then be passed out through any known form of outlet. The valve 19 is provided with a shifting device 23, whereby it may be moved to bring either of the openings 20 into communication with the corresponding port 18. A valve 24 is located upon each of the valves 19 and is provided at one end with an opening 25 and at the opposite end with a larger opening 26, which may be made to register with the opening 20 in the valve 19 irrespective of the said valve 19. A valve-seat 27 is located above each of the valves 24, and valves 28 are mounted upon said valve-seats 27. Suitable operating connections 29 are provided and are connected to the shaft 10 by means of the eccentric and rods 30, thereby automatically operating the said valves.

My improved engine is simple, durable, and efficient and consists of a minimum number of parts, none of which can easily become

dislocated or disconnected. The engine may be made very light and when in operation produces great power.

I claim—

1. In a rotary engine, cylinder-heads having steam-chambers formed in their inner sides, projecting cam-surfaces in said chambers, abutments pivotally supported in said cam-surfaces, a piston having steam-chambers formed in its sides, projecting cam-surfaces in said chambers, abutments carried within said cam-surfaces against which the steam is forced to rotate the said piston, and means whereby the piston may be driven in either direction, substantially as specified.

2. A rotary engine having a piston provided with steam-chambers at its sides, cam-surfaces having grooves or depressions in said steam-chambers, cylinder-heads having corresponding steam-chambers formed in their inner sides, cam-surfaces having grooves in said steam-chambers, abutments pivotally carried by said piston and by said cylinder-heads within the said grooves and extending into and closing the steam-chambers, and means whereby the steam may be admitted to drive the piston in either direction, substantially as specified.

3. The improved rotary engine, consisting of cylinder-heads having steam-chambers formed in their inner surfaces, a rotary piston located between said cylinder-heads and having corresponding steam-chambers formed in its sides, movable abutments carried by the cylinder-heads and being pivoted at their inner ends and extending into the steam-chambers formed in the piston, movable abutments pivotally carried by the piston and extending into the steam-chambers formed in the cylinder-heads, and means whereby the abutments may pass each other while the piston is rotating, substantially as specified.

4. The improved rotary engine, consisting of a rotary piston having steam-chambers formed in its sides, entrance-ports leading to said steam-chambers, abutments carried within said steam-chambers so that the piston will be rotated when steam is driven into the steam-chambers, valves located within the steam-ports, means for automatically operating said valves, and means for shifting the valves so that the piston may be driven in either direction.

In testimony whereof I affix my signature in presence of two witnesses.

CHARLES D. BENNETT.
